US00D665423S

(12) **United States Design Patent**
Impas et al.

(10) **Patent No.:** **US D665,423 S**
(45) **Date of Patent:** **** Aug. 14, 2012**

(54) **DISPLAY SCREEN WITH AN ICON**

(75) Inventors: **Romualdo T. Impas**, Seattle, WA (US);
Anne Loomis Thompson, Seattle, WA (US);
Jeff J. Lin, Seattle, WA (US);
Diane Shambaugh, Redmond, WA (US)

(73) Assignee: **Microsoft Corporation**, Redmond, WA (US)

(**) Term: **14 Years**

(21) Appl. No.: **29/406,158**

(22) Filed: **Nov. 10, 2011**

Related U.S. Application Data

(62) Division of application No. 29/380,190, filed on Dec. 1, 2010, now Pat. No. Des. 650,800.
